UNITED STATES PATENT OFFICE.

FRANCIS L. SPRING, OF TOWNSEND, MASSACHUSETTS.

SHINGLING-BRACKET.

953,981.

Specification of Letters Patent.

Patented Apr. 5, 1910.

Application filed January 22, 1909. Serial No. 473,682.

To all whom it may concern:

Be it known that I, FRANCIS L. SPRING, a citizen of the United States, residing at Townsend, in the county of Middlesex and State of Massachusetts, have invented new and useful Improvements in Shingling-Brackets, of which the following is a specification.

This invention relates to an improved shingling bracket, and the object is to provide a light, strong bracket which may be adjusted to fit roofs of different pitches and which may be readily folded so as to occupy but little space; and the object is further to provide a bracket of this class, the base of which may be secured to the shingles by nails, and after a course of shingles has been laid on top of the base of the bracket the same may be readily disconnected from the nails without lifting the shingle which lies upon the base.

A still further object is to provide a strong and convenient device for securing to the bracket the adjustable stop against which rests the plank upon which the workmen sit.

In the attainment of the objects above enumerated, I have produced a bracket which is simple in construction and economical to manufacture.

The invention consists in the novel features of construction and in the combination and arrangement of parts set forth in the following specification and particularly pointed out in the appended claims.

Referring to the drawing: Figure 1 is a plan of a shingling bracket embodying my invention, the same being shown in place on the shingles of a roof. Fig. 2 is a sectional

view taken on line 2—2 of Fig. 1. Fig. 3 is a side elevation of the bracket when folded.

Like numerals refer to like parts throughout the several views of the drawing.

In the drawing, 5 is a base comprising two plates 6 and 7. To the plate 6 is secured a yoke 8, to which yoke a pair of arms 9, 9 are pivoted at 10, said arms terminating at their lower ends in spurs 11 adapted to stick into the roof of the building. To the plate 7 is secured a bracket 12 to which bracket a pair of arms 13, 13 are pivoted at 14, said arms being pivoted at

15 to the arms 9. The arms 13 are adapted to support the usual plank 16, said plank being held in position on said arms by means of a stop 17 adjustably secured to 55 said arms by means of a clamp screw or bolt 18 extending between said arms and through a clamp plate 19 located on the under side thereof, a thumb nut 20 having screw-threaded engagement with said screw being 60 provided to coöperate with said screw and clamp plate to secure the stop 17 to the arms 13, it being understood that said stop may be adjusted longitudinally of said arms for different widths of planks. 65

In order that the arms 13 and planks 16 may be approximately horizontal regardless of the pitch of the roof the angle of the arms 9 and 13 to each other and to the base 5 may be varied by moving the plates 6 and 70 7 longitudinally of each other, said plates for that purpose being adjustably connected together preferably in the following manner. The plate 6 is provided with a series of holes 21, while the plate 7 is pro- 75 vided with a projection 22 formed thereon or secured thereto, which projection is adapted to enter any one of said series of holes. Embracing the plates 6 and 7 is a slide 23 which normally holds said plates 80 against lateral displacement relatively to each other, said slide being adapted to be moved from the position shown in Fig. 2 toward the right out of engagement with the plate 6 and when said slide is thus disen- 85 gaged the plate 6 may be lifted until the projection 22 passes out of the hole 21 in which it is located and said projection may then be placed in another hole of the series, thus changing the length of the base 5 and 90 consequently changing the angular relation of the arms 9 and 13 to each other and to said base, it being understood that the slide 23 is again moved toward the left so as to embrace both of the plates. The plate 7 is 95 provided adjacent to the free end thereof with two preferably V-shaped notches 24 and 25 extending thereinto from opposite edges, respectively, thereof, said notches being located out of alinement with each other lon- 100 gitudinally of said plate, said plate being preferably narrowed somewhat at its right hand extremity.

In the use of the bracket, the workman, standing upon a scaffold at the side of the house, lays upon the roof several courses of shingles, the number shown in the drawing being five. He then places two or more of the brackets upon the courses of shingles thus laid, in the position shown and drives into the upper course of shingles two nails 26 and 27 in the notches 24 and 25, respectively, as shown in Fig. 1. These nails, when thus driven, prevent the bracket from sliding downwardly on the slope of the roof, the spurs 11 also tending to prevent such sliding movement as well as preventing lateral movement of the bracket.

It will be noted that the arms 9, 9 diverge toward the lower ends thereof in such a manner as to give the bracket considerable rigidity laterally. The plank 16 is then laid upon the brackets in the usual manner and the workman sitting thereon then lays several more courses of shingles up on the slope of the roof as far as he can reach. After these new courses of shingles have been laid, other brackets are then put in place thereon in the manner hereinbefore described and subsequently the series of brackets previously used lower down on the roof are removed in the following manner. Each bracket is lifted slightly to disengage the spurs 11 from the shingles and said bracket is then swung laterally from the position shown in full lines in Fig. 1 to the position indicated in dotted lines therein so that the plate 7 may then be withdrawn from between the nails 26 and 27 and subsequently the workman strikes the shingle above said nails to drive them fully into the roof so that said shingle will lie in close contact with the shingle therebeneath.

When it is so desired, the bracket may be conveniently folded so as to occupy but a small amount of space, this being accomplished by first loosening the stop 17 and moving the same from the position shown in Fig. 2 to a position adjacent to the pivot 14. The slide 23 is then moved toward the right out of engagement with the plate 6 and said plate is then lifted until the projection 22 passes out of the hole 21 in which the same is located. The arms 13 are then swung in the direction of the arrow *a*, Fig. 2, through an angle of somewhat less than 90° and the plate 6 is then swung in the direction of the arrow *b* until the same rests against the upper side of the arms 9. The arms 9 are then swung in the direction of the arrow *c* until they very nearly coincide with the plane of the arms 13. The arms 13 are then swung in the direction of the arrow *d* until the parts occupy the position shown in Fig. 3, the bracket when thus folded being very compact and occupying but a small amount of space.

Having thus described my invention, what I claim and desire by Letters Patent to secure is:

1. A shingling bracket, having in combination, a base comprising two plates, means to adjustably secure said plates to each other, two arms pivotally connected to each other, and pivots connecting said arms to said plates, respectively.

2. A shingling bracket, having in combination, a base comprising two plates, a projection on one of said plates, the other of said plates being provided with a hole in which said projection is located, means to hold one of said plates against lateral movement relatively to the other, two arms pivotally connected to each other, and pivots connecting said arms to said plates, respectively.

3. A shingling bracket, having in combination, a base comprising two plates, means to hold one of said plates against movement longitudinally of the other, means to hold one of said plates against lateral movement relatively to the other, and pivots connecting said arms to each other and to said plates, respectively.

4. A shingling bracket, having in combination, a base comprising two plates, means to detachably secure said plates to each other, two arms pivotally connected to each other, and pivots connecting said arms to said plates, respectively.

5. A shingling bracket, having in combination, a base comprising two plates, one of which is provided with a series of holes, a projection on the other of said plates adapted to enter any one of said holes, a device adapted to embrace both of said plates to hold the same against lateral displacement relatively to each other, said device being slid able longitudinally of both of said plates and being adapted to be disengaged from one of said plates to permit lateral displacement thereof, two arms pivotally connected to each other, and pivots connecting said arms to said plates, respectively.

6. A shingling bracket, having in combination, a base comprising two plates constructed to interlock with each other to prevent movement of one longitudinally of the other, a slide adapted to embrace both of said plates to hold the same against lateral displacement relatively to each other, said slide being adapted to be moved longitudinally thereof out of engagement with one of said plates to permit lateral displacement thereof, and two arms pivotally connected to each other, said arms being also pivotally connected to said plates.

7. A shingling bracket, having in combination, a base adapted to rest upon a roof, two arms pivoted to each other and pivots connecting said arms to said base, one of

said arms being provided with a spur adapted to engage said roof.

5. A shingling bracket, having in combination, a base adapted to rest upon a roof, a pair of arms pivoted to said base and having spurs adapted to engage said roof and another pair of arms pivoted to said base and to said first-named pair of arms.

In testimony whereof I have hereunto set my hand in presence of two subscribing witnesses. 10
